UNITED STATES PATENT OFFICE.

MAXIMILIAN CHARLES SCHWEINERT, OF NEW YORK, N. Y.

CLOSURE FOR ICE BAGS.

Application filed November 10, 1921, Serial No. 514,253. Renewed April 30, 1926.

This invention relates to closures for ice bags, and aims to provide certain improvements therein. The invention is particularly directed to an improvement in a device of the class described, wherein the closure is formed with a nipple or socket member which is connected with the bag and a cap comprising a metal structure having in the preferred form a central aperture at its top with a packing gasket on the under side of the flange formed by the aperture, and a covering forming preferably an integral structure with the packing gasket.

The present invention is an improvement upon this general construction, by means of which the fastening of the closure to the ice bag is simplified and the entire structure cheapened.

According to the present invention the socket member and cap are formed of sheet metal, and the socket member is connected to the bag by a threaded sleeve, thus avoiding the necessity of vulcanizing the socket member to the ice bag. The invention also includes certain other features of improvement which will be hereinafter more fully pointed out.

Referring to the drawings, which illustrate several forms of the invention,—

Fig. 1 is an elevation of the socket member and sleeve, the cap being partly shown with the covering in section.

Fig. 2 is a diametrical section.

Fig. 3 is a view, showing various sections on the lines 3—3 in Fig. 2.

Fig. 4 shows another form of the invention in diametrical section.

Fig. 5 is an elevation of the socket member of Fig. 4.

Fig. 6 is a diametrical section of another form of the invention.

Fig. 7 is an elevation of the metallic cap, socket member, and sleeve of Fig. 6.

Fig. 8 shows sections taken on the lines 8—8 in Fig. 6.

Referring first to Figs. 1 to 3 of the drawings, let A indicate a socket member, which is shown as formed of sheet metal, having a thread B rolled thereon and having a bottom flange C. Preferably the bottom flange has its edge turned over at D, so as to prevent cutting of the rubber. The socket member is inserted within the neck of the rubber bag, the flange C lying beneath the wall of the latter, and preferably the wall being reinforced by a patch of fabric or rubber F.

Screwing on the exterior of the socket member is a clamping sleeve G, which is also preferably formed of sheet metal, and is provided with a flange H adapted to engage the upper side of the body of the ice bag, whereby when screwed home the bag is clamped between the flanges C and H and thus adequately held in place. In the construction shown the metallic cap member J is formed also of sheet metal, and has a thread rolled in it to engage the thread B of the socket member. The sheet metal cap is perforated on its top, so as to leave a flange K, and the rubber cover L is moulded on the inside and outside of the flange, thus forming a packing which engages the seat M formed on the top of the socket member. Preferably the rubber covering is extended entirely over the exterior of the cap.

The flange K is preferably corrugated as shown at N, so as to make a holding surface for the rubber. This produces a slight swell in the rubber around the interior of the cap where the packing seats against the seat M, which is advantageous in that it provides a depressed ring around the packing which facilitates the forming of a tight joint with the seat. In order that the socket member may secure a better grip on the rubber of the bag, whereby to prevent loosening under torsional strains when the cap is being screwed and unscrewed, I provide projections O (see Fig. 3) which are stamped up from the flange C, and which enter the rubber when the clamping ring G is screwed tight. Similar projections may be formed on the clamping ring, as shown for instance in Figs. 6 and 8.

In Figs. 4 and 5 I have illustrated a modified form in which the socket member A' is arranged on the outside of the bag, and the clamping sleeve G' is arranged on the inside. By this means the socket member may be very considerably shortened as compared with the structure of Figs. 1 to 3. In Figs. 1 to 3 the depth of the socket member must be sufficient to permit the use of the outside clamping sleeve G, and also the cap. In the construction of Figs. 4 and 5 the clamping sleeve engages the inside of the socket member, and the cap the outside of the socket member, so that these parts may clamp as shown, and a cheapened construction produced.

In Figs. 6 to 8 a similar construction is provided, with the exception that the flange

D' of the socket member is made wider than the flange J' of the interior clamping ring. This is for the purpose of enabling the user to grasp the flange D' of the socket member while the cap is being screwed on and unscrewed. Under these conditions the screwing and unscrewing of the cap would have no tendency to loosen the clamping ring G². While I have shown and described several forms of the invention, it will be understood that I do not wish to be limited thereto, as various changes may be made therein without departing from the spirit of the invention.

15 What I claim is:—

1. A closure for ice bags or the like, comprising a socket member having a flange adapted to contact with the outer wall of a bag and an internal clamping ring having a similar flange adapted to contact with the interior wall of the bag, said clamping ring screwing on the interior of the socket member.

2. A closure for ice bags or the like, comprising a socket member having a flange 25 adapted to contact with the outer wall of a bag and an internal clamping ring having a similar flange adapted to contact with the interior wall of the bag, said clamping ring screwing on the interior of the socket member, and the clamping ring having a flange 30 extending beyond the flange on the socket member.

3. A closure for ice bags or the like, comprising a socket member having a flange 35 adapted to contact with the outer wall of a bag and an internal clamping member having a similar flange adapted to contact with the interior wall of the bag, said clamping ring screwing on the interior of one of 40 said members, and the socket member having a flange extending beyond the flange on the other member.

In witness whereof, I have hereunto signed my name:

MAXIMILIAN CHARLES SCHWEINERT.
